CLAIM

The ornamental design for a golf club training accessory, as shown and described.

DESCRIPTION

FIG. 1 is a front perspective view of a golf club training accessory showing the new design;

FIG. 2 is a front elevation view of the golf club training accessory of FIG. 1;

FIG. 3 is a rear elevation view of the golf club training accessory of FIG. 1;

FIG. 4 is a right side view of the golf club training accessory of FIG. 1;

FIG. 5 is a left side view thereof of the golf club training accessory of FIG. 1;

FIG. 6 is a top view thereof of the golf club training accessory of FIG. 1;

FIG. 7 a bottom view thereof of the golf club training accessory of FIG. 1; and,

FIG. 8 is a rear perspective view of a golf club training accessory of FIG. 1.

The broken lines are included for the purpose of illustrating non-claimed subject matter and form no part of the claimed design.
